Primary Examiner — Mark A Goodwin(74) *Attorney, Agent, or Firm* — Talus Law Group LLC(57) **CLAIM**

The ornamental design for the detector holder arm posterior, as shown and described.

DESCRIPTION

FIG. 1 is a perspective view of the detector holder arm posterior showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a perspective environmental view thereof.

The dashed lines refer to environment and form no part of the claimed design.

1 Claim, 7 Drawing Sheets(56)
